UNITED STATES PATENT OFFICE.

NORRIS C. LEONARD, OF NASHVILLE, TENNESSEE, ASSIGNOR TO THE CROWN COMPANY, OF NASHVILLE, TENNESSEE, A CORPORATION OF TENNESSEE.

EMBROIDERY-HOOP.

1,232,817.

Specification of Letters Patent.

Patented July 10, 1917.

Application filed January 11, 1916. Serial No. 71,520.

To all whom it may concern:

Be it known that I, NORRIS C. LEONARD, a citizen of the United States, and a resident of Nashville, in the county of Davidson and State of Tennessee, have invented 5 certain new and useful Improvements in Embroidery-Hoops; and I do hereby declare the following to be a full, clear, and exact description of the invention, such as 10 will enable others skilled in the art to which it appertains to make and use the same.

This invention relates to improvements in embroidery hoops, and more particularly to that class in which the outer hoop member 15 is adapted to be expanded and contracted,—the object of the invention being to provide simple and efficient devices which may be cheaply manufactured and easily applied to the outer hoop member for 20 quickly effecting the expansion or contraction thereof.

A further object is to provide adjusting devices for an embroidery hoop, which shall be substantial in construction and which shall 25 not be liable to become distorted or out of order,—at the same time insuring accurate alinement of the inner faces of the hoop member at the meeting ends of the same.

With these and other objects in view, the 30 invention consists in certain novel features of construction and combinations of parts as hereinafter set forth and pointed out in the claims.

In the accompanying drawings; Figure 1 35 is a view in elevation illustrating my improvements; Fig. 2 is an edge view partly in section; Fig. 3 is a transverse sectional view, and Fig. 4 is a rear face view.

1 represents the outer hoop member of a 40 pair of embroidery hoops, the ends of which are made with diagonal meeting ends and these ends are caused to approach or recede from each other to effect the contraction or expansion, with the use of my improvements.

45 A plate 2 is securely riveted near one end to the hoop member, near the end 3 thereof, and is of sufficient length to project well over and beyond the beveled end 4 of the hoop member,—such projecting end of the 50 plate being made with an elongated slot 5 and strengthened by a bead 6. A rivet 7 (preferably of the tubular type) is secured to the end portion 4 of the hoop member and projects through the slot 5, the free 55 end of said rivet being headed or enlarged

so as to overhang the side walls of the slot. It will be observed that the end portions 3—4 of the hoop member are permanently connected by the plate, but that the portion 4 is movable relatively to said plate. The 60 headed rivet 7 serves to assist in guiding the portion 4 of the hoop, and said hoop portion 4 is furthermore guided by inwardly-turned flanges 8 at the respective edges of the plate. The plate 2 is enlarged 65 as at 9 and made with a central circular opening 10. The sides of the enlarged portion 9 are bent downwardly and inwardly so as to form continuations of the guide flanges 8 and so as also to form flanges 70 11 which will embrace the side edges of the end portion 3 of the hoop and prevent pivotal movement of the same relatively to the plate 2.

A wheel or button 12 mounted on the 75 enlarged portion 9 is made with a disk or bottom 13, the peripheral portion of which projects under the inner face of the plate while the edge portion of the wheel or button is disposed over that portion of the 80 plate which surrounds the opening 10. The wheel or button 12 is thus mounted on the plate in such manner that it may be turned freely but is effectually prevented from escape or displacement, while the disk or bottom 13 of said wheel or button occupies the 85 opening 10 in the plate.

The disk or bottom 13 of the wheel or button 12 is made with a spiral slot 14 through which a headed rivet 15 projects, 90 said rivet being rigidly secured to the movable end portion 4 of the hoop, preferably at one side of the longitudinal center thereof.

From the above description and the drawing, it will be apparent that when the wheel or button 12 is turned in one direction, the coöperation of the walls of the spiral slot with the rivet 15 will cause the beveled ends of the hoop to separate and the hoop to be 100 expanded, and that when the wheel or button is turned in the reverse direction, said beveled ends will be caused to approach each other so as to contract the hoop, and clamp material between the latter and an inner 105 hoop (not shown) with which it is used.

Having fully described my invention what I claim as new and desire to secure by Letters-Patent, is:—

1. The combination with a divided em- 110

broidery hoop, of a plate riveted at one end to one end portion of the hoop and having an intermediate opening, said plate having an elongated slot in its other end portion, 5 a rivet secured to the other end portion of the hoop, said rivet projecting through said elongated slot and having a headed free end, a button revolvably mounted over the intermediate opening in the plate and carried by the latter, said button having a part provided with a spiral slot, and a projection on the hoop to enter said spiral slot.

2. The combination with a divided embroidery hoop, of a plate overlying the divided portion of the hoop and having flanges embracing the side edges thereof, said plate also having an intermediate opening, means rigidly securing said plate to one end portion of the hoop, means movably connecting said plate with the other end portion of the hoop, a button revolvably mounted on and carried by the plate and having a disk occupying the intermediate

opening in the plate, said disk having a spiral slot, and a projection on the movable end portion of hoop and passing through said spiral slot.

3. The combination with a divided embroidery hoop, of a single plate rigidly secured to one end portion of the hoop and overlying the other end portion of the hoop, means movably connecting said overlying portion of the plate to the hoop, a button revolvably mounted on and carried by said plate and having a spiral slot, and a headed rivet secured to an end portion of the hoop at one side of the longitudinal center of the same and passing through said spiral slot.

In testimony whereof, I have signed this specification in the presence of two sub- 40 scribing witnesses.

NORRIS C. LEONARD.
